CLAIM

The ornamental design for a product display pusher device, as shown and described.

DESCRIPTION

FIG. 1 is a perspective view of a product display pusher device showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the encircled portion labeled "9" in FIG. 2.

The dash-dash broken lines depict portions of the product display pusher device that form no part of the claimed design. The dash-dot broken lines in FIGS. 2 and 9 demarcate enlarged areas and form no part of the claimed design.

1 Claim, 9 Drawing Sheets
